MACHINE FOR APPLYING MOBILE FILMS

Peter J. Massey, River Forest, Ill., and William F. Thiele and Bert F. Rapraeger, Wisconsin Rapids, Wis., assignors, by mesne assignments, of nine-tenths to Consolidated Water Power & Paper Company, Wisconsin Rapids, Wis., a corporation of Wisconsin, and one-tenth to Peter J. Massey, Chicago, Ill.

Application September 11, 1935, Serial No. 40,159

18 Claims. (Cl. 91—50)

This invention relates to improvements in coating devices and refers specifically to a machine for coating paper for printing purposes, the device being characterized in that the coating material is applied to one or both surfaces of a continuously advancing web by means of rolls, the coating being in its finished condition as initially applied necessitating no further working after its application to the web.

One of the important features of our invention resides in the provision of one or more sets of distributing rolls whereby the coating material is worked prior to its transfer to the applicator rolls, the axes of the distributing rolls of each set being disposed in substantially the same horizontal plane, whereby deflection of said rolls is in the same direction and a uniform nip pressure is secured along the entire length of each of the rolls to work the coating material forward uniformly.

Another important feature of our invention resides in means whereby all osculating rolls may be adjusted with respect to each other to within a fraction of one-thousandth of an inch, the adjusting means being such as to permit adjustment during operation of the machine.

A further feature of our invention comprises means whereby all of said osculating rolls may be conveniently separated from each other and returned to osculating position without in anywise altering the original adjustment hereinbefore mentioned.

Another feature of our invention resides in the provision of pneumatic means for urging the osculating rolls toward each other and pneumatic means for spacing or separating said rolls.

A further feature of our invention resides in the use of a pair of rolls for metering the coating material, the speeds of said rolls being changeable to control the thickness of the film of coating material passed to the distributing rolls.

Another feature of our invention comprises the provision of cleaning rolls, for cleaning the applicator rolls, said cleaning rolls having hard porous surfaces of the character of artificial stone, and said rolls being urged into contact with said applicator rolls by pneumatic means.

A further object of our invention comprises the use of blasts of hot air directed to the passing coated web in such a manner as to eliminate wrinkles and to set and dry the coating materials; also the use of blasts of hot air directed between the web and drying rolls over which the web is trained to cushion the coated web upon said rolls and thus prevent injury to the coating.

Other objects and advantages of our invention will be apparent from the accompanying drawings and following detailed description.

In the drawings, Fig. 1 is a diagrammatic side elevational view of our coating device. 5

Fig. 2a is an enlarged view of a portion of the coating machine.

Fig. 2b is an enlarged view of the remaining portion of the machine complementary to that shown in Fig. 2a. 10

Fig. 3 is a fragmentary side elevational view of one of the metering rolls, illustrating particularly the dams at the end of the rolls.

Fig. 4 is an elevational view of the apparatus shown in Fig. 3. 15

Fig. 5 is a transverse sectional view taken through the hot air chambers above and below the passing web.

Fig. 6 is a plan view, either top or bottom, of the hot air chambers shown in Fig. 5. 20

Referring in detail to the drawings, 1 indicates the coating machine comprising our invention, said machine being particularly adaptable for carrying out the processes described in the patents to Peter J. Massey, Patents Nos. 1,921,368 and 1,921,369. The machine 1 can be operated as a coating unit per se, in which case any type of coating may be applied to either or both surfaces of any type of flexible web, or the machine may be used as a unit of a paper making machine, in which case said machine is preferably interposed between banks or batteries of dryers. In the latter case, of course, the coating will be applied to a fibrous web, either paper or board passed directly from the paper forming portion 35 of the paper machine after preliminary drying.

For purposes of example the machine is herein described in the latter mentioned environment, namely, in conjunction with a paper making machine and the coating applied to the paper web 40 is adapted to be such as to render a surface or the surfaces of the web suitable for printing.

The machine comprises essentially two sets of substantially similar instrumentalities designated generally at 2 and 3, being the mechanisms for respectively coating the upper and lower faces of a paper web 4 which passes continuously from the preliminary dryers 5. The web 4 after being coated is passed to the final dryers 6 wherein the web is dried to the desired degree. The upper mechanism 2 is suspended from a frame 7 which is supported by columns 8 and 9. The lower mechanism 3 may be mounted immediately beneath the mechanism 2. 45

Referring particularly to Fig. 2a, 10 indicates 50

55

a cylinder in which a piston 11 is positioned, said piston being connected to piston rod 12 which passes through the head of the cylinder 10. Cylinder 10 may be mounted upon trunnions or bearings 13 whereby said cylinder may be rocked upon movement of piston rod 12. The end of piston rod 12 is connected to rod 13 which is journaled at its ends in opposite frame members 14. The frame members 14 are supported at their bottoms in oppositely positioned lugs or brackets 15, the supporting connection comprising a pivot 16 whereby the frame members may be rocked. Means (not shown) are provided whereby air or fluid under pressure may be introduced into cylinder 10 either above or below piston 11, or, if desired, a vacuum may be established above or below piston 11 within cylinder 10. In either case, piston 11 can be moved upwardly or downwardly in cylinder 10 which, of course, causes cylinder 10 to rock about bearings 13 and frames 14 to rock about pivots 16. The purpose of so operating this mechanism will be hereinafter fully described.

A pair of standards 17 may be pivotally mounted upon frame members 14, said standards being swingable or rockable about pivots 18. The upper ends of each of the standards 17 carry bearings 19 which support roll 20 between them. A pair of standards 21 may be rigidly mounted upon frame member 14, said standards carrying bearings 22 which support roll 23. A bushing 24 is pivotally secured, as at 25, to an upper extension of standards 17 upon each side of the machine, said bushing being adapted to receive one end of screw 26, said screw being threaded in said bushing. A bushing 27 is pivotally secured to an upper extension of each standard 21, the opposite end of screw 26 being threaded in said bushing. A capstan 28 is mounted upon the central portion of screw 26. The arrangement is such that, upon rotation of capstan 28 and therefore screw 26, rolls 20 and 23 may be adjusted with respect to each other, the opposite ends of screw 26 having pitches of opposite direction or the opposite threads may be pitched in the same direction but of different degree.

Referring particularly to the upper mechanism 2, the apparatus hereinbefore described is substantially duplicated. However, said apparatus is in inverted position and is carried by the frame 7. A cylinder 29 is carried upon bearings 30, a piston 31 being slidably movable within said cylinder and secured to a piston rod 32 which in turn is connected to rod 33 which is carried between opposite frame members 34. Frame members 34 are pivotally secured to lugs 35 upon each side of the machine which, in turn, are carried by frame 7.

Standards 36 and 37 are mounted in spaced relationship upon each frame member 34, said standards carrying bearings 38 and 39 respectively between which rolls 40 and 41 are mounted. The outer ends of standards 36 and 37, in this case, the lower ends, are adjustably tied together by means of screw 42 which carries capstan 43, the ends of said screw being threadedly engaged in bushings 44 and 45, pivotally mounted upon standards 36 and 37 respectively. Similar to the corresponding apparatus in the lower mechanism 70 3, the contiguity of rolls 40 and 41 may be controlled.

Rolls 20 and 23 and rolls 40 and 41, hereinafter referred to as fountain or gate rolls, are adapted to carry in their respective nips a quantity of liquid or semi-liquid coating material which is

delivered therefrom through appropriate agencies to the coating rolls, all of which will be hereinafter described.

Rolls 20, 23, 40 and 41 are covered with rubber, the rubber covering 46 on rolls 20 and 40 being of relatively high density and the rubber covering 47 on rolls 23 and 41 being a medium hard rubber. The rolls per se are constructed of metal, preferably of a non-corrosive type, and the rubber coverings 46 and 47 extend short of each end of the roll, as shown best in Fig. 3. In order to retain the coating material in the nip of the rolls, each set of gate rolls is provided at each end with a pair of dams 48 and 49, dams 48 riding over the rubber coverings and dams 49 riding over the metal rolls adjacent the ends of the covering. A water pipe 50, controlled by valve 51 discharges in the spaces between each of the dams 48 and 49 and serves to lubricate said dams, said dams being of a material readily lubricated by water.

All of the rolls 20, 23, 40 and 41 are preferably of the same overall diameter and are preferably separately driven. In operation, rolls 23 and 41 are driven counter-clockwise and rolls 20 and 40 are driven clockwise. Rolls 23 and 41 are adapted to carry a film, of desired thickness, of coating material which is adapted to be transferred to rolls osculating therewith, hereinafter described. Obviously, in utilizing a machine such as herein described it is desirable to apply different types of coating materials and different weight or quantities of coating to the web. In our machine such control is obtained primarily by the gate rolls 20, 23, 40 and 41. To exercise such control in addition to the proper manipulation of caps 28 and 43 which control the contiguity of each pair of rolls, said rolls are adapted to be driven at different peripheral speeds, that is, rolls 20 and 40 will be driven at a different speed than rolls 23 and 41. It is preferred that the drive of rolls 23 and 41 be such as to drive said rolls from a speed equal to the speed of the rolls to which the film of coating material is transferred to a speed approximately one-fourth as much. Rolls 20 and 40 are driven over a maximum range of speed preferably from one revolution per minute to full speed corresponding to the maximum speed of rolls 23 and 41.

In practice, a "Ward Leonard" drive is utilized to drive rolls 20 and 40, said drive (not shown) comprising a direct current motor energized by a direct current generator both being separately excited and the generator being driven by any suitable prime mover. The speed of the motor may be controlled from approximately half speed to full speed by means of variation of the motor field current, that is, by reducing the field current for higher speeds and increasing the field current for lower speeds. The speed of the motor for speeds less than half speed is controlled by varying the impressed voltage upon the motor armature which is accomplished by varying the generator field current. To vary the speed of rolls 23 and 41 a mechanical speed changer of the "Reeves" or "link belt" type is used, the speed changer being driven by any suitable means (not shown). It is obvious that the greater the differential in peripheral speed between rolls 21 and 23 and 40 and 41, the less will be the thickness of coating film applied to rolls 23 and 41 and hence less coating material will be transferred to the system.

In the lower mechanism the film of coating material is transferred from roll 23 to distributing roll 52 which revolves in a clockwise direction.

- The film is transferred therefrom to distributing roll 53 which revolves in a counter-clockwise direction, thence to roll 54 which revolves clockwise. From roll 54 the film is transferred to form rolls 55 and 56 both of which revolve in a counter-clockwise direction. Form rolls 55 and 56 transfer the film to coating roll 57 which revolves in a clockwise direction and by which the film is applied to one surface of the web 4.
- 10 In the upper mechanism 2, the film of coating material carried upon the surface of roll 41 is transferred to the surface of roll 58, which revolves in a clockwise direction. From roll 58 the film of coating material is transferred to roll 59 which rotates in a counter-clockwise direction. Roll 59 passes the film to roll 60 which revolves in a clockwise direction. Roll 60 transfers the film of coating material to the surface of roll 61 which rotates in a counter-clockwise direction.
- 15 From roll 61 the film is passed to rolls 62 and 63, both of which revolve in a clockwise direction. The form rolls 62 and 63 pass the film from their surfaces to the surface of the upper coating roll 64 whereby said film is applied to the upper surface 20 of the web 4 simultaneously with the application of a similar film to the lower surface thereof by roll 57.
- Rolls 57 and 64 revolve at the same peripheral speed which is equal to the linear speed of web 4.
- 25 30 In the lower mechanism 3 rolls 52, 53, 54, 55 and 56 all revolve at the same peripheral speed as roll 57 and in the upper mechanism 2 rolls 58, 59, 60, 61 and 62 and 63 revolve at the same peripheral speed as coating roll 64. It will be noted that all of the rolls comprising the lower mechanism 3 with the exception of the form rolls 35 35 40 45 50 55 60 65 70 75 55 and 56 have their axes disposed in the same horizontal plane. Similarly all of the rolls comprising the upper mechanism 2 with the exception of the form roll 62 and 63 have their axes disposed in a common horizontal plane. In transferring the films of coating material from the coating rolls 57 and 64, the thickness of said film must be controlled to a fine degree of accuracy. The film in passing from roll to roll throughout the upper and lower mechanisms is worked and smoothed by such passage and said rolls consequently must be carefully adjusted with respect to their contiguity. It is well known that members of relatively great weight such as the rolls herein used, being supported only at their ends, deflect due to their weight. By disposing substantially all of the rolls in a common horizontal plane, the deflection of all of said rolls is in the same direction and a film of uniform thickness may be carried throughout the entire surface of each of the rolls. This is a very important feature of our invention in view of the fact that the films of coating applied to the web are applied as finished films necessitating no further working after application to the web. Consequently said film must be prepared with the highest degree of accuracy and care, particularly with respect to its thickness. In addition, it will be noted that the rolls comprising the upper and lower mechanisms, that is, rolls 58, 59, 60, 61, 62 and 63 and rolls 52, 53, 54, 55 and 56 are all of different diameters.
- It can readily be seen that inasmuch as the peripheral speeds of all of said rolls are equal, the fact that the diameters are different prevents the surfaces of adjacent rolls from repeatedly contacting along the same line. In other words, a portion of the surface of roll 52, which at one revolution contacts a predetermined portion of the surface of roll 53, will not again contact said predetermined portion for a long period of time. In this manner the surfaces of the rolls are maintained in uniform condition and ridges will not be formed upon the coating film carried upon the surfaces of the rolls. In order that the direction of rotation of the coating rolls be correlated with respect to the direction of rotation of the gate rolls in both the upper and lower mechanisms, an additional roll is provided 10 in the upper mechanism 2, namely roll 58, which serves merely as an agency for changing the direction of rotation.
- Roll 52 is carried by bearings 65 which, in turn, are carried by standards 66 positioned upon each side of the machine. Standards 66 are pivotally mounted as at 67 to lugs 68. Each of the standards 66 is provided with upward extensions 69 which carry guides 70. A bearing block 71 is slidably positioned in said guides and may be adjusted upwardly or downwardly by means of capstan screw 72. A roll 73 may be journalled in bearings 71 and is adapted to be disposed in oscillating position with respect to roll 52. Roll 73 is an idler roll and is driven only by means of its contact with roll 52. Roll 73 in so contacting roll 52 assists in working and smoothing the film of coating material carried by roll 52.
- Roll 53 is carried at each of its ends in bearings 74 which, in turn, are carried at the upper ends of standards 75 positioned at each side of the machine, said standards being pivotally mounted as at 76 upon lugs 77. In the case of both rolls 52 and 53, conventional means (not shown) is provided for oscillating said rolls longitudinally simultaneously with their rotation, which action further assists in working and smoothing the coating material carried upon their peripheral surfaces.
- Roll 54 is carried by bearings 78 which, in turn, are mounted upon standards 79 positioned at each side of the machine, said standards being pivotally supported as at 80 upon lugs 81.
- Roll 56 is carried by bearings 82 which are slidably positioned in guides 83, said guides being carried by standards 84 upon each side of the machine.
- Standards 84 are pivotally mounted as at 85 upon lugs 86. Bearings 82 may be moved upwardly or downwardly thereby moving roll 56 upwardly or downwardly by means of the adjusting capstan screw 87. Roll 55 is carried by bearings 88 which, in turn, are carried by standards 89 also pivotally mounted upon lugs 86 as at 85. Standards 89 comprise a frame which embraces a portion of standards 84 and the center line of bearings 88 can be changed with respect to the center line of bearings 82 by means of set screws 90 threadedly positioned upon opposite sides of each of the standards 89 and adapted to bear upon the guide portions of standards 84.
- Rolls 58, 59, 60, 61, 62 and 63 are mounted in substantially the same manner as rolls 52, 53, 54, 55 and 56. To facilitate and simplify the description only those portions of the upper mechanism associated with said rolls which differ from the lower rolls will be described. In view of the fact that rolls 58 to 63 inclusive are positioned above the passing web 4, said rolls are disposed upon suspended supports, all of said supports being pivotally connected to the frame 1. Roll 60 has associated therewith an idler roll 91 which is journalled in bearings 92 movable 75

in guides 93. The function of the roll 91 is similar to that of roll 73, said roll being adapted to bear upon the surface of roll 60 and is driven only through its contact with roll 60. Similar to rolls 52 and 53 rolls 59 and 60 may be oscillated longitudinally by conventional means (not shown). The mounting of rolls 62 and 63 is similar to that of rolls 55 and 56 with the exception that the standards which carry rolls 62 and 63 are suspended.

Rolls 57 and 64 are rubber covered similar to wet felt press rolls at the wet end of a paper machine. Rolls 55, 58, 62 and 63 are also rubber covered, the rubber being of low density and relatively soft. Rolls 54 and 61 are covered with rubber having a comparatively high density, or, if desired, said rolls may be uncovered and constructed of a non-corrosive metal. Rolls 53 and 60 are covered with comparatively soft rubber and roll 91 is covered with medium hard rubber as is also roll 73. Rolls 52 and 59 are covered with a medium hard rubber or, if desired, may be of a non-corrosive metal construction. Roll 58 is covered with a medium hard rubber.

Coating rolls 57 and 64 are preferably driven by means of conventional cone pulleys and belt (not shown) from the indriving shaft of dryers 5 and 6 as the coating roll must be driven from either one source or the other in order to provide means for taking care of the draw of the paper web. The entire coating machine may be driven from the indriving shaft of dryer 5 or the indriving shaft of dryer 6. Rolls 53, 54, 55 and 56 and rolls 58, 59, 60, 61, 62 and 63 may be driven from rolls 57 and 64 through a suitable train of gears and indriving shafts (not shown). In place of said gear train, if desired, the indriving shafts of rolls 57 and 64 may drive alternating or direct current generators. Either alternating or direct current motors may then drive the rolls, above mentioned through suitable reducing gears, each roll being driven by a separate motor. If an alternating current generator is driven by the indriving shaft of rolls 57 and 64 the usual induction motors of relatively high speed and relatively small diameter may be used and the correct peripheral speed is obtained by means of the gear ratio between the motor and the rolls. As the speed of the rolls 57 and 64 is changed from time to time the induction motors will follow as the slip on the induction motor changes very little with the change in frequency of the generator. On account of the simplicity of operation of the induction motors they are preferred to direct current motors, however, a direct current generator and direct current motors may be used by separately exciting all of the direct current motors and generator. The voltage of the generator will then vary with the speed of rolls 57 and 64 and consequently the speed of the direct current motors will vary as the impressed voltage varies and thereby the speed of the rolls will follow the speed of the coating rolls.

As has been hereinbefore described the efficacy of our machine resides in the ability to apply a film of predetermined thickness and quality to the surface of a passing web. To obtain such film the material is passed over the surfaces of a plurality of distributing rolls which passage works the coating material upon the surfaces of the rolls and reduces the film to the proper thickness and smoothness. Obviously, therefore, it is essential that close control be maintained of the

proximity or contiguity of the various oscillating rolls. To obtain this minute control is one of the primary features of our invention.

A bushing 94 is pivotally secured to the frame member 14 as at 95, said bushing being positioned in a recess 96 in said frame. Another bushing 91 is pivotally connected to a pin 98 carried by standard 86, said bushing being provided with a slot 99 in which pin 98 is adapted to be positioned. A screw 100 is threadedly positioned at each of its ends in bushings 94 and 91 respectively, said screw being operable by means of a capstan 101. The arrangement is such that by manipulation of capstan 101, standard 86 and frame member 14 may be positioned a desired distance from each other and, consequently, the surfaces of rolls 23 and 52 may be positioned a predetermined distance from each other. Screw 100 functions as a spacer and when operating to control the distance between rolls 23 and 52, said screw acts as a compression member, roll 23 being urged toward roll 52 by means of compressed air in the lower portion of cylinder 10. The threads at opposite ends of screw 100 may be pitched in opposite directions or said threads may be pitched in the same direction but of a different degree. In this manner the proximity or contiguity of roll 23 with respect to roll 52 may be very closely controlled. In practice this proximity may be controlled to a fraction of one-thousandth of an inch.

In a similar manner the proximity of rolls 52 and 53 are controlled, a bushing 102 being pivotally secured to pin 98 and a bushing 103 being pivotally secured to pin 104 carried by standard 75, bushing 103 being provided with a slot similar to slot 99. Bushings 102 and 103 may be operatively connected by means of capstan screw 105 which functions similar to screw 100 to control the spacing or degree of contiguity of rolls 52 and 53.

The spacing of roll 53 with respect to roll 54 is controlled by means of an arrangement similar to those described with respect to rolls 23 and 52, and rolls 52 and 53. In view of the fact that the mechanism is identical with that hereinabove described, it is believed that the same will be apparent to those skilled in the art without further description.

An arm 106 is carried by bearing 78, said arm in turn carrying pin 107. Bearing 88 is provided with an arm 108 which carries pin 109. A bushing 110 may be pivotally secured to pin 109 and a bushing 111 may be pivoted to pin 107, said bushing being provided with a slot 112. A capstan screw 113 operatively connects bushings 110 and 111 in a manner similar to the capstan screws hereinbefore described. By this arrangement it can readily be seen that standard 89 which carries roll 55 may be spaced a desired distance from standard 79 which carries roll 54 and inasmuch as standards 89 and standards 84 may be adjusted relative to each other, the manipulation of capstan screw 113 also controls the relative positions of standards 79 and 84. In this manner the degree of contiguity or proximity of roll 54 and rolls 55 and 56 may be controlled.

Coating roll 57 is mounted upon bearings 114 which, in turn, are supported by standards 115. Bearing 114 carries an upwardly extending lug 116 which, in turn carries pin 117. Bearing 88 has an outwardly extending arm 118 which carries pin 119. A bushing 120 is pivotally secured to pin 118 and a bushing 121 is pivotally connected to pin 117, said last mentioned bushing 75

being provided with an elongated slot 122 in which pin 117 is adapted to be disposed. A capstan screw 123 operatively connects bushings 120 and 121 and controls the degree of contiguity 5 of rolls 55 and 56 with respect to the coating roll 57.

The arrangement for controlling the contiguity or proximity of the rolls constituting the upper mechanism 2 is identical with that described in 10 conjunction with the lower mechanism, and to facilitate and clarify the description and prevent duplication said control mechanism will not be described in detail.

As has been hereinbefore described, the various 15 capstan screws between the adjacent rolls function as spacers or compression members when the device is in operation. All of said rolls are brought to the predetermined position determined by the adjustment of said capstan screws 20 by means of the application of air or other fluid under superatmospheric pressure within the lower portion of cylinder 10. It can readily be seen that when piston 11 acts to move frame member 14 in clockwise direction, pins 98, 104, 107 and 117 25 will be positioned at the extreme left end of the slots in which said pins are respectively positioned. It frequently happens that the web 4 breaks. This is a common occurrence in a paper mill. If the web happens to break while passing 30 over the various distributing rolls comprising the lower mechanism, said web would tend to wind upon one or more of the rolls. Obviously if this situation occurred the winding web would tend 35 to force the rolls away from each other. However, in view of the fact that all of the rolls are ultimately urged towards each other by means of fluid under pressure within cylinder 10, a broken web would not cause any breakage in the machine 40 since piston 11 would merely be urged against a cushion of air under superatmospheric pressure within cylinder 10.

In addition, in view of the fact that close adjustment of the proximity of the rolls is of vital 45 importance, it is desirable that the breakage of a web such as above described, would not throw said rolls out of adjustment. Further, it may be desired to separate each of the rolls from one another without changing the ultimate adjustment of the rolls. Each of these situations can 50 be taken care of in our machine without the necessity of laboriously re-adjusting the rolls.

If it is desired to separate the rolls as hereinbefore described, it is merely necessary to introduce fluid under pressure above piston 11 within 55 cylinder 10 and relieve the pressure below said piston. When this is done rolls 55 and 56 are rocked about pivot 85 in a counter-clockwise direction and are separated from roll 57 a distance substantially equal to the length of the slot 122. Similarly roll 54 rocks about pivot 80 and is separated from rolls 55 and 56 a distance 60 equal to the length of slot 112. In like manner each of the rolls 53 and 52 rock in a counter-clockwise direction about pivots 76 and 67 respectively a distance equal to the length of the slots in bushings 97 and 103. The frame member 14 also rocks in a counter-clockwise direction a distance substantially equal to the summation of the distances comprising the various 65 slots. However, rolls 20 and 23 do not separate in view of the fact that both of said rolls move with frame member 14 as a unit. By this arrangement the coating material carried in the nip of said rolls is still retained therein. It 70 can readily be seen that after said rolls have been

separated in the manner hereinabove described, fluid under pressure may be applied to the lower side of piston 11 and the pressure may be relieved from the upper side of said piston. The resulting action of the piston moves all of the standards in a clockwise direction about their various pivotal supports until the pins carried by the standards again contact the left ends of the various bushing slots. It can readily be seen that in this manner the machine is ready for 10 instant operation without the necessity of re-adjusting the capstans. 5

The same operation can also be carried out with respect to the upper mechanism 2. However, in the case of the upper mechanism the 15 standards rotate about their suspending pivots. If the rolls are to be maintained in separated relationship for a considerable period of time, it is not necessary to maintain pressure on the upper portion of piston 11 within cylinder 10 since 20 the standards will remain in their canted position under the influence of gravity. However, in view of the fact that the upper standards would tend to return to contiguous position, means is provided for positively holding the frame member 25 34 in rocked position thereby holding all of the upper standards in canted position. This means comprises a platform 124 which is swingably positioned upon pin 125 carried by bracket 126 mounted upon column 8. Pin 125 comprises 30 an extension of rod 127 which carries at its lower end a bevel gear 128 which meshes with bevel gear 129 carried upon shaft 130. A hand wheel 131 is rigidly connected to shaft 130 and functions to rotate said shaft together with shaft 35 127. When air under pressure is introduced into cylinder 29 at the lower side of piston 31 and frame member 34 is rocked in a clockwise direction, platform 124 is swung to a position substantially parallel to column 8. After frame 40 member 34 has been brought to the position shown in dotted lines in Fig. 2a, platform 124 is rotated by means of hand wheel 131 to its extended position whereby the end of frame member 34 can be supported. In this 45 manner the upper rolls may be maintained in spaced relationship without the necessity of maintaining a continuous supply of fluid under pressure for cylinder 29.

To wash or clean rolls 52, 53, 54, 55, 56 and 50 57, and rolls 58, 59, 60, 61, 62, 63 and 64, means is provided whereby frame members 14 and 34 may be rocked to separate rolls 23 and 52 and rolls 41 and 58 without separating the remaining rolls. This means comprises a bushing 132 55 having a forked end 133 which is adapted to embrace an eccentric (not shown) carried by pin 134. An arm 135 is keyed to pin 134 and is adapted to rotate said eccentric. A bushing 136 may be pivotally connected to an intermediate 60 portion of standard 66, said bushing being provided with a slot 137 which embraces pin 138 secured to said standard. A capstan screw 139 operatively connects bushings 132 and 136, said screw being similar to, and functioning in a 65 manner similar to the remaining capstan screws.

The arrangement is such, that when arm 135 is rotated through an angle of 180° from the position shown, the capstan screw 139 together with bushings 132 and 136 are effectively lengthened 70 thereby rocking frame member 14 in a counter-clockwise direction against the fluid pressure within cylinder 10 beneath piston 11. This action, of course, separates rolls 23 and 52 without effecting the relative positions of the remaining 75

rolls. Similar apparatus is provided in connection with the upper mechanism 2, said apparatus functioning in an identical manner. When the gate rolls are separated from the distributing rolls in the manner described, a relatively large quantity of water may be discharged upon the distributing rolls while they are running in contrast with one another thereby effectively cleaning said rolls. Of course, paper is not being made during this period.

Roll 64, unlike roll 57 which is mounted upon the fixed bearing 114, is mounted upon a floating bearing 140 which is pivotally secured at 141 to standard 142 which, in turn is supported by frame 7. Bearing 140 has an outwardly extending arm 143 which is pivotally and slidably associated with rod 144, the connection between arm 143 and rod 144 being buffered or cushioned by coil springs 145. Rod 144 is threaded at its upper end and engages with a power driven worm wheel. As the worm wheel rotates in one direction rod 144 is raised and when rotated in the opposite direction, rod 144 is moved downwardly. By this arrangement the contacting pressure of roll 64 may be controlled by raising or lowering rod 144. This arrangement is old in the art and comprises no part of our invention.

A cleaning roll 148 is disposed in contacting relationship with coating roll 57. A similar cleaning roll is associated with coating roll 64 and the mechanism to be hereinafter described relative to said cleaning roll is duplicated in the mechanism 2. Roll 148 is mounted upon bearings 149 which in turn are supported by standards 150, pivotally mounted at 151 to lugs 152. Each of the standards 150 may be provided with an outwardly extending arm 153 which is pivotally connected at its end to piston rod 154. A piston 155 is mounted upon the end of piston rod 40 154 which is adapted to be slidably positioned within fluid cylinder 156. Cylinder 156 is pivotally mounted at 157 to supporting lug 158. The arrangement is such that when fluid under pressure is introduced into cylinder 156 beneath piston 155, standard 150 is urged in a counterclockwise direction thereby bringing roll 148 into continuous relationship with roll 57.

A bushing 159 is pivotally connected at 160 to standard 115. A bushing 161 is pivotally connected to standard 150, said bushing being provided with a slot 162 which is adapted to embrace pin 163 secured to standard 150. A capstan screw 164 is connected at its ends to bushings 159 and 161 and is adapted to control the spacing between rolls 148 and 57. A set screw 165 is threaded into the standard 150, the end thereof projecting into recesses 166 in which bushing 161 is positioned. By the provision of said set screw the movement of standard 150 60 away from standard 115 and, consequently, the movement of roll 148 away from roll 57 may be controlled.

Such movement, that is, clockwise movement of standard 150 may be obtained by introducing fluid under pressure into cylinder 156 above piston 155 and relieving the pressure below said piston.

Roll 148 and its companion roll in the upper section are adapted to serve as cleaning rolls for the coating rolls 57 and 64 respectively. In view of the fact that the films of coating material applied to the surfaces of the web 4 are in their finished condition immediately after application, it is obvious that any accumulations or deposits upon either of the coating rolls would tend to dis-

rupt or disfigure said film. Consequently, the cleaning rolls hereinabove described are provided. The roll 148 and its companion roll in the upper mechanism have relatively hard porous surfaces and may be constructed of stone, "Stonite" or 5 other artificial stone. Accumulations or deposits removed from rolls 57 and 64 by the cleaning rolls are scraped therefrom by means of the blades 167, which, in turn, are mounted upon brackets 168 supported by arms 169.

Web 4 after passing between coating rolls 57 and 64 has deposited upon its surfaces a film of coating material. In order that said material can be deposited in its final smooth form it must contain a substantial quantity of moisture. Consequently, when web 4 leaves the coating rolls its surfaces contain a coating material which is relatively moist. A conduit 170 supported at one end by means of bracket 171 secured to the supporting rod 172 is positioned above the path of travel of the web 4. In like manner a conduit 173 is supported by means of bracket 174 to the supporting rod 172, said latter conduit being positioned beneath the path of travel of the web. Both conduits 170 and 173 are provided with discharge openings or nozzles 175 and said conduits are connected to a suitable source of warm or hot air under pressure which is discharged into contact with the upper and lower coated surfaces of the web 4. After passing between conduits 170 and 173 the web is trained around guide roll 176. In passing over said guide roll warm or hot air under pressure is discharged through nozzles 177 provided in the wall of an arcuate conduit 178 which comprises a vertical extension of conduit 170. After passing over guide roll 176 the web 4 is trained over drier roll 179 which comprises one roll of the drier bank 6. In passing over roll 179 warm or hot air under pressure is discharged through nozzles 180 provided in an arcuate conduit 181 which conforms with a portion of the periphery of roll 179.

The end of conduit 173, namely, that end which is adjacent roll 176 is provided with a series of nozzles 182 which discharge streams of air between the lower face of the web 4 and the surface of roll 176. In this manner a film of air is provided between the lower face of the web and the surface of the roll and, consequently, the coating upon said web is not detrimentally affected by the contact with the surface of roll 176. In like manner discharge nozzles 183 in conduit 178 discharge warm or hot air between web 4 and the surface of the drier roll 179, the purpose being similar to that hereinbefore described.

In order to prevent wrinkling or roping of the web 4 after the coating has been applied thereto, the nozzles 175 which direct the hot air into contact with the coated surfaces of the web are arranged to place the web under a relatively slight transverse tension. To accomplish this, the nozzles 175 in both the upper and lower conduits 170 and 173, adjacent the edges of the web, have their center-lines at an angle, as shown at 184 and 185 in Figs. 5 and 6, and the nozzles 175 adjacent the center of the web have their axes at right angles to the web surfaces, as shown at 186. It can readily be seen that the air discharged from nozzles 184 and 185 produces a component of force which tends to stretch the web transversely, thereby preventing the formation of wrinkles. Moreover, the center-lines or axes of the nozzles 175 are inclined in the direction of travel of the web, thereby tending to stretch the web longitudinally.

Nozzles 182 and 183 across the width of the respective conduits are of varying diameters so that a greater quantity of air is discharged at the longitudinal center of the web than at its edges, whereby the web as it passes over rolls 176 and 179 bellies outwardly, the greatest bulge being at the center of the web. In this manner, the air is more or less trapped between the rolls and the web and substantially insulates the web 10 from the surfaces of said rolls, thereby preventing deformation of the newly laid coating.

By the expression "contacting" as used in the claims with respect to the relationship of the various rolls, is meant that, the peripheries of 15 adjacent rolls are sufficiently close to permit contact of and actual transfer of the film from roll surface to roll surface.

We claim as our invention:

1. A coating machine for coating continuously 20 advancing flexible webs which comprises in combination, a juxtaposed pair of oppositely driven rolls having uniform surfaces between which said flexible web passes, means for applying a preformed film of coating material to the surface of 25 each of said rolls whereby said films are transferred to said web, each said means comprising a plurality of contacting distributing rolls disposed with axes in substantially the same horizontal plane whereby deflection of said rolls occurs in the same direction and does not change the degree of contact between adjacent distributing 30 rolls, and means for applying a metered quantity of coating material to said distributing rolls.

35 2. A coating machine for coating continuously advancing flexible webs which comprises in combination, a juxtaposed pair of oppositely driven rolls between which said flexible web passes, means for applying a preformed unbroken film of 40 coating material to the surface of each of said rolls whereby said films are transferred to said web, each said means comprising a plurality of contacting distributing rolls, means for applying a metered quantity of coating material to said 45 distributing rolls, and adjustable means for maintaining said rolls at a predetermined degree of proximity with respect to each other.

3. A coating machine for coating continuously 50 advancing flexible webs which comprises in combination, a juxtaposed pair of rolls between which said flexible web passes, means for applying a preformed film of coating material to the surface of one of said rolls whereby said film is transferred to said web, said means comprising a 55 plurality of supports movable relative to each other, contacting distributing rolls carried by said supports, means for applying a metered quantity of coating material to said distributing rolls, and compressed fluid means for maintaining said supports and rolls at a predetermined degree of proximity with respect to each other.

4. A coating machine for coating continuously 60 advancing flexible webs which comprises in combination, a juxtaposed pair of rolls between which said flexible web passes, means for applying a preformed film of coating material to the surface of each of said rolls whereby said films are transferred to said web, each said means comprising a plurality of contacting distributing rolls, means 65 for constantly applying a metered quantity of coating material to said distributing rolls, and means for adjusting the distributing rolls with respect to their proximity to each other.

5. A coating machine for coating a continuous- 70 ly advancing flexible web which comprises in

combination, a pair of juxtaposed coating rolls between which said flexible web passes, means for applying a preformed film of coating material to the surface of each of said rolls, whereby said film is applied to opposed surfaces of the web, 5 means for working and smoothing said film prior to its application to each of said coating rolls comprising a pair of sets of distributing rolls, each set comprising a plurality of distributing rolls disposed in series with their axes in substantially 10 the same horizontal plane, said distributing rolls being constantly in contact with each other and with said coating rolls, and means for constantly applying a measured quantity of coating material to each set of distributing rolls. 15

6. A coating machine for coating continuously advancing flexible webs which comprises in combination, a juxtaposed pair of rolls between which said flexible web passes, means for constantly applying a preformed film of coating material to substantially the entire surface of each of said rolls whereby said films are transferred to said web, said means comprising two series of contacting distributing rolls, and means for applying a metered quantity of coating material to each 20 series of said distributing rolls comprising two pair of horizontally juxtaposed gate rolls, means for maintaining a quantity of coating material in the nip of each pair of said gate rolls, one of the 25 gate rolls of each pair contacting each one of 30 said distributing rolls.

7. A coating machine for coating continuously advancing flexible webs which comprises in combination, a juxtaposed pair of rolls between which said flexible web passes, means for applying a preformed film of coating material to the surface of one of said rolls whereby said film is transferred to said web, said means comprising a plurality of contacting distributing rolls, means for applying a metered quantity of coating material to said distributing rolls comprising a pair of horizontally juxtaposed gate rolls, means for maintaining a quantity of coating material in the nip of said gate rolls, one of said gate rolls contacting one of said distributing rolls, and means 40 for independently driving said gate rolls at different peripheral speeds. 45

8. A coating machine for coating continuously advancing flexible webs which comprises in combination, a juxtaposed pair of rolls between which said flexible web passes, means for applying a preformed film of coating material to the surface of one of said rolls whereby said film is transferred to said web, said means comprising a plurality of contacting distributing rolls, means for applying a metered quantity of coating material to said distributing rolls comprising a pair of horizontally juxtaposed gate rolls, means for maintaining a quantity of coating material in the nip of said gate rolls, one of said gate rolls contacting one of said distributing rolls, means for independently driving said gate rolls at different peripheral speeds, and means for varying the ratio of said peripheral speeds. 60

9. A coating machine for coating continuously advancing flexible webs which comprises in combination, a juxtaposed pair of rolls between which said flexible web passes, means for applying a preformed film of coating material to the surface of one of said rolls whereby said film is transferred to said web, said means comprising a plurality of contacting distributing rolls, means for applying a metered quantity of coating material to said distributing rolls, and means for 70 cleaning said coating roll comprising a roll hav- 75

ing a dry, porous surface disposed in contact with said coating roll at its receding side with respect to the web.

10. A coating machine for coating continuously advancing flexible webs which comprises in combination, a juxtaposed pair of rolls between which said flexible web passes, means for applying a preformed film of coating material to the surface of one of said rolls whereby said film is transferred to said web, said means comprising a plurality of contacting distributing rolls, means for applying a metered quantity of coating material to said distributing rolls, and means for cleaning said coating roll comprising a roll having a hard, porous surface disposed in contact with said coating roll at its receding side with respect to the web.

11. A coating machine for coating continuously advancing flexible webs which comprises in combination, a juxtaposed pair of rolls between which said flexible web passes, means for applying a preformed film of coating material to the surface of one of said rolls whereby said film is transferred to said web, said means comprising a plurality of contacting distributing rolls, means for applying a metered quantity of coating material to said distributing rolls, means for cleaning said coating roll comprising a roll having a hard, porous surface disposed in contact with said coating roll at its receding side with respect to the web, and pneumatic means for maintaining said cleaning roll in contact with said coating roll.

12. A coating machine for coating continuously advancing flexible webs which comprises in combination, a juxtaposed pair of oppositely rotating rolls between which said flexible web passes, means for applying a preformed film of coating material to the surface of each of said rolls whereby said films are transferred to said web, each of said means comprising a plurality of contacting distributing rolls, means for constantly applying a metered quantity of coating material to said distributing rolls, and means for driving said distributing rolls and coating rolls at the same peripheral speed.

13. A coating machine for coating continuously advancing flexible webs which comprises in combination, a juxtaposed pair of rolls between which said flexible web passes, means for applying a preformed film of coating material to substantially the entire surface of each of said rolls whereby said films are transferred to said web, said means comprising two series of contacting distributing rolls, means for applying a metered quantity of coating material to each series of distributing rolls, and means for discharging a blast of hot air into contact with the coated surfaces of the web after its passage between said juxtaposed rolls.

14. A coating machine for coating continuously advancing flexible webs which comprises in combination, a juxtaposed pair of rolls between which said flexible web passes, means for applying a preformed film of coating material to the surface of one of said rolls whereby said film is transferred to said web, said means comprising a plurality of contacting distributing rolls, means for applying a metered quantity of coating material to said distributing rolls, means for drying

said web after its passage between said juxtaposed rolls, comprising a plurality of heated drums over which said web passes, and means for discharging heated air under pressure between said web and the surface of a heated drum to provide an insulating film of air between the coated surface of the web and the surface of said drum.

15. A coating machine for coating continuously advancing flexible webs which comprises in combination, a juxtaposed pair of rolls between which said flexible web passes, means for applying a preformed film of coating material to the surface of one of said rolls whereby said film is transferred to said web, said means comprising a plurality of contacting distributing rolls, means for applying a metered quantity of coating material to said distributing rolls, means for discharging heated air under pressure into contact with said coated web, said means being so constructed as to exert opposite components of force transversely of said web whereby said web is subjected to transverse tension.

16. A coating machine for coating continuously advancing flexible webs which comprises in combination, a juxtaposed pair of oppositely driven coating rolls between which said flexible web passes, means for applying a preformed film of coating material to the surface of each of said rolls whereby said films are transferred to said web, said means comprising two series of distributing rolls, the rolls of each series being in contact with each other and with a coating roll, and means for constantly applying a metered quantity of coating material to each series of distributing rolls.

17. A coating machine for coating continuously advancing flexible webs which comprises, in combination, a juxtaposed pair of rolls between which said flexible web passes, means for applying a preformed film of coating material to the surface of each of said rolls whereby said films are transferred to said web, each of said means comprising a plurality of distributing rolls disposed in substantially the same horizontal plane, means for constantly applying a metered quantity of coating material to said distributing rolls, and micrometric means for adjusting the distributing rolls with respect to their proximity to each other.

18. A coating machine for coating continuously advancing flexible webs which comprises in combination a juxtaposed pair of rolls between which said flexible web passes, means for applying a preformed film of coating material to the surface of one of said rolls, whereby said film is transferred to said web, said means comprising a plurality of contacting distributing rolls, means for applying a metered quantity of coating material to said distributing rolls comprising a pair of horizontally juxtaposed gate rolls, means for maintaining a quantity of coating material in the nip of said gate rolls, one of said gate rolls contacting one of said distributing rolls, and means for driving said gate rolls at a speed independent of the speed of the distributing rolls.
